UNITED STATES PATENT OFFICE.

MERLE M. STEARNS, OF VENTURA, CALIFORNIA.

FLASH LIGHT.

Application filed June 27, 1927. Serial No. 201,912.

My invention relates to flash lights of the dry cell type.

It is a purpose of my invention to provide a flash-light of the type above specified which is capable of being readily positioned upright on a horizontal support, and its lamp housing adjusted laterally to project light rays in any direction desired, thus eliminating the heretofore necessity of holding the flash-light 10 to secure the desired illumination.

I will describe only one form of flash-light embodying my invention, and will then point out the novel features thereof in claims.

In the accompanying drawings;

Fig. 1 is a view showing in side elevation and partly in section one form of flash-light embodying my invention;

Fig. 2 is an enlarged fragmentary section of the flash-light shown in Fig. 1;

Fig. 3 is a sectional view taken on the line 3—3 of Fig. 2;

Fig. 4 is a horizontal sectional view taken on the line 4—4 of Fig. 1.

Referring specifically to the drawings in which similar reference characters refer to similar parts in each of the views, my invention in its present embodiment comprises an elongated tubular casing 15 formed of any suitable metal and exteriorly threaded at its 30 upper end for the reception of a screw cap 16, the latter being formed integral with a ball head 17, which may be solid or hollow as shown. At the junction of the ball head and cap an inwardly extending annular shoulder 35

18 is provided which serves to confine a filler ring 19 in firm contact with a disc 20 of insulating material in clamped position upon the upper end of the casing. The casing 15 is adapted to receive the conventional dry

40 cell 21 as used in flash lights of this type, and as is conventional the cell is provided with a terminal 22 which is engaged by a contact 23 riveted to the disc 20 and to a conducting arm 24, which extends upwardly into the ball head

45 with its upper end secured to an arcuate member 25 having its outer surface serrated to form a rack. The ball head 17 is provided with a slot spanned by an arcuate strip 26 of insulating material suitably secured to the

50 ball head and provided with an opening 26^a through which the upper end of the arm 24 extends. The rack 25 is secured to the strip 26 so as to be insulated from the conducting material of which the ball head 17 is formed.

55 A lamp housing 27 is mounted on the ball head 17 for pivotal movement through the

medium of a pin or shaft 28 journaled in the ball head and secured at its opposite ends to a socket member 29, which, in the present instance, is constructed from the same sheet of metal of which the housing 27 is formed. This socket member conforms generally in contour to the ball head 17, and by virtue of its mounting is capable of being swung from the upright position shown in Fig. 2 to the horizontal position shown in dot and dash lines and to thereby effect lateral adjustment of the lamp housing as a whole through an arc of 90°. In order that the lamp housing may assume the horizontal position the socket 60 is recessed as indicated at 30 to accommodate the adjacent portion of the screw cap 16.

The lamp housing 27 is provided with the usual lens 31, reflector 32, and lamp 33, the latter engaging a contact 34 riveted to a cap 35 of insulating material and having a threaded base engaging within a collar 36 with the latter secured to an outstruck portion 37 of the socket member 29. As shown in Fig. 2 the cap 35 is of rectangular form in 70 cross section, its base being rounded for engagement with the collar 36. Movable vertically within the cap is a contact brush 38 urged downwardly by a spring contact 39 riveted to the cap and electrically connected 75 to the contact 34. The lower end of the brush 38 is tapered as shown in Fig. 2 for engagement with the serrations of the rack 25 and to thereby provide a latching device by which the lamp housing is releasably secured in any 80 position of adjustment through the connection of the brush 38 with the lamp 33 and the connection of the rack 25 with the cell terminal 22. It will be clear that the rack and brush serve to conduct current from the cell 85 to the lamp, the other side of the circuit being through the lamp housing socket member 29, ball head 17 of the casing 15 which is in electrical contact with the cell. Thus in any 90 position of adjustment of the lamp housing 95 27 current may be supplied to illuminate the lamp 33. It will, of course, be understood that this circuit is controlled by the conventional switch 40 on the casing 15 as shown in 100 Fig. 1.

As shown in Figs. 1 and 4 the lower end 105 of the casing 15 is exteriorly threaded to receive a bottom cap 41 which is preferably of hexagonal form, the bottom of the cap being concave as indicated at 41^a. A cap so constructed provides a relatively broad base 110 for supporting the casing in upright position

with a greater degree of security than is possible with the conventional circular cap. The concave bottom permits the cap to set level on the uneven surface of a support and minimizes the tendency of the casing to tip.

In practise the lamp housing can be adjusted through an arc of 90° so as to focus the light rays to any point within the arc, it being necessary to exert sufficient force on the lamp housing to overcome the latching tendency of the brush 38. However, when once the adjustment is secured the brush in its coaction with the rack serves to maintain the lamp housing in adjusted position. When positioning the flash-light vertically as shown in Fig. 1, it is, of course, unnecessary to hold the flash light in the hand as it may be positioned on a substantially horizontal support, and by adjusting the lamp housing together with a circumferential adjustment of the casing, light rays can be projected in any direction desired. Further, when the flash-light is occupying a horizontal position, the lamp housing can still be adjusted laterally to project the light rays in any direction horizontally, any rolling tendency of the casing being prevented by virtue of the hexagonal form of the bottom cap 41.

Although I have herein shown and described only one form of flash-light embodying my invention, it is to be understood that various changes and modifications may be made herein without departing from the spirit of the invention and the spirit and scope of the appended claims.

I claim as my invention:

1. A flash-light comprising a casing for a dry cell, a top cap on the casing, a ball head on the top cap, a lamp housing, a ball socket on the lamp housing pivoted on the ball head, and means for conducting current from the cell to the lamp housing, said means including a latching device for securing the ball socket in any position of adjustment and comprising an arcuate rack on the ball head and a spring-pressed pawl on the ball socket engaging the rack.

2. A flash light comprising a casing for a dry cell, a cap on the casing, a ball head on the cap, a rack secured to the ball head and insulated therefrom, means by which the rack is adapted to be electrically connected to the cell in the casing, a socket member pivoted on the ball head for swinging movement, a spring pressed brush carried by the socket

member and yieldably engaging the rack, a lamp housing on the socket member, and means by which the brush is adapted to be electrically connected to the lamp of said housing.

3. A flash light as embodied in claim 2 wherein the first mentioned means comprises a conducting arm secured to the rack, a disc member within the cap, and a contact secured to the disc and connected to the arm and adapted for contact with one terminal of the cell in said casing.

4. A flash light comprising a casing, a cap on the casing, a ball head on the cap having a slot therein, an insulating member secured within the slot, a rack member of conducting material secured to the insulating member, a pin extending through the ball head, a socket member secured to said pin for swinging movement on the ball head, said socket member having an outstruck portion, a cap threaded in said portion, a spring pressed brush movable in said cap and engaging said rack to latch the socket member against movement, a lamp housing on the socket member, and an electrical connection between said brush and the lamp of said housing.

5. A flash-light of the dry cell type comprising a casing, a ball-head at one end of the casing having a conducting arm terminating at one end axially of the casing, a contact element exterior of the ball head and connected with said arm, and a lamp housing movably mounted on the ball head and having a contact element in movable engagement with the first mentioned contact element and having means to establish circuit connections with a lamp carried by the housing, the said one end of the conducting arm adapted to be engaged directly with the pole piece of a cell contained within said casing.

6. A flash-light of the dry cell type comprising a casing, a ball head at one end of the casing having a conducting arm, a contact element on the ball head and connected to said arm, and a lamp housing movably mounted on the ball head and having a contact element in movable engagement with the first mentioned contact element and having means to establish circuit connections with a lamp carried by the housing, and to coact therewith to hold the housing in a position of selected adjustment.

MERLE M. STEARNS.
